Primary Examiner — George D. Kirschbaum*Assistant Examiner* — Maria J Edwards(74) *Attorney, Agent, or Firm* — Lyon & Harr, LLP; Richard T. Lyon(57) **CLAIM**

The ornamental design for fit over eyeglasses, as shown and described.

DESCRIPTION

FIG. 1 is a perspective view of a fit over eyeglasses showing my new design;

FIG. 2 a front elevation view of FIG. 1;

FIG. 3 is a top plan view of FIG. 1; and,

FIG. 4 is a side elevation view of FIG. 1.

The broken lines in the drawings depict environmental structure and form no part of the claimed design.
